UNITED STATES PATENT OFFICE.

SANTIAGO PAGÉS MARUNY AND JUAN BAUTISTA PAGÉS MARUNY, OF BARCELONA,
SPAIN.

PACKAGE FOR CONTAINERS OF PHARMACEUTICAL PRODUCTS AND THE LIKE.

1,381,487.

Specification of Letters Patent. Patented June 14, 1921.

Application filed August 6, 1920. Serial No. 401,704.

To all whom it may concern:

Be it known that we, SANTIAGO PAGÉS MARUNY and JUAN BAUTISTA PAGÉS MARUNY, subjects of the King of Spain, residing at Barcelona, Spain, have invented new and useful Improvements in Packages for Containers of Pharmaceutical Products and the like, of which the following is a specification.

10 Our invention relates to packages for containers of pharmaceutical products and the like, particularly containers for liquids for injection, which are generally formed with a tubular portion and with sealed stems extending therefrom, and the particular object of our invention is to provide means for packing these containers in a package containing a number of them such that the removal of each particular container from the package shall be definitely and surely indicated, in order that substitutions of other containers for those originally packed may not take place without such substitution or replacement being apparent.

25 Our invention consists in the construction, combination and arrangement of parts described and claimed in the specification and illustrated in the accompanying drawings. In the drawings, which show preferred embodiments of the invention, similar reference characters designate corresponding parts, and

Figure 1 shows a package in perspective view, with parts broken away, for use with tubes having stems at one end only; and

Fig. 2 shows, in perspective view, a package containing tubes having stems at both ends.

Referring to the drawings, the package itself may consist of a box C with a cover K and a number of partitions D secured therein and arranged to eliminate material sideways movement of the tubes A. The tubes A are arranged between the partitions D with their stems B inserted in a band F, preferably paper, having openings E adapted to receive the stems; this band F being secured in place in the box after the insertion of the stem portions of the tubes in the openings E. In this way movement of the tubes in other than the one direction necessary to lift them out, is eliminated by the construction of the package, including the bottom, the sides and ends and the partitions, while in order to lift out a tube it

is necessary to break the portion of the band F corresponding with that tube. Due to this construction, even after the removal of one or more tubes, the remaining tubes are secured against removal without detection. 60

When the tubes to be packed are those having a stem at one end only, we prefer to insert in the box an inclined false bottom so that a single band is sufficient to prevent the removal of any container by inclining it without breaking the band. Under the stems there may be arranged packing or wadding G of suitable material to prevent their breakage, which should not, however, be soft enough to permit of the stem 65 being pressed into it and to allow the other end of the tube to be raised above the edge of the box, as this would permit the removal of a tube without breaking the band, and would negative the advantage of the inclined bottom. 70

As shown in Fig. 2, if the tubes have stems at both ends, the preferred method of holding them is to supply a band at each end having openings adapted to receive the 80 stems, eliminating the necessity for any packing such as the wadding G preferably used in the case of single stem tubes.

In operation, the tubes are arranged with the bands in place over the stems and placed 85 in the box between the partitions. The bands are then firmly secured in the box, preferably by adhesive material, of sufficient strength to prevent their removal without damage. In use a tube is removed by 90 lifting it out, breaking the corresponding portion of the band. Since the construction of the box prevents movement of the tube in any direction but that controlled by the band, even after some of the tubes 95 have been removed, the remaining ones can be taken out only by breaking the corresponding portion of the band, or otherwise mutilating the box. Thus replacement or substitution of tubes can be immediately and 100 surely detected.

Having now described our invention, we claim and desire to secure by Letters Patent:

1. A package for containers of pharmaceutical products and the like, including 105 means for indicating the removal of and preventing substitution for a container, originally packed, comprising a band having openings through which portions of the containers extend secured in the package, and 110

means to prevent removal of a container other than by breaking a portion of said band.

2. A package for containers of pharmaceutical products and the like, including means for indicating the removal of and preventing substitution for a container originally packed, comprising a band having openings through which portions of the containers extend secured in the package, and means to prevent movement of the containers in other than one direction, said band being arranged to restrain each container in that direction until broken by removal of 15 such container.

3. A package for containers of pharmaceutical products and the like, including means for indicating the removal of and preventing substitution for a container originally packed, comprising a band having openings through which portions of the containers extend secured in the package, separating partitions fixed in said package between the containers to prevent sidewise 20

movement thereof, and means to prevent end 25 movement, thereby rendering said containers individually removable only on breaking of portions of said band.

4. A package for containers of pharmaceutical products and the like, including 30 means for indicating the removal of and preventing substitution for a container originally packed, comprising an inclined bottom arranged in said package, partitions to separate said containers secured in said package, a band having openings through 35 which stem portions of said containers extend secured in said package, means in said package to prevent endwise movement of said containers, said inclined bottom being arranged co-operatively with said band and containers to prevent removal of the latter without breaking the band by lifting one end thereof.

In testimony whereof we have signed our 45 names to this specification.

SANTIAGO PAGÉS MARUNY.

JUAN BAUTISTA PAGÉS MARUNY.
